United States Patent Office

Des. 177,563
Patented May 1, 1956

177,563

AIRPLANE OR SIMILAR ARTICLE

Wendell S. Fletcher, South Pasadena, Calif.

Application November 22, 1954, Serial No. 33,189

Term of patent 14 years

(Cl. D71—1)

FIG. 1.

FIG. 2.

FIG. 3.

Figure 1 is a top view of an airplane, or similar article, showing my new design;

Figure 2 is a front view of the same airplane; and

Figure 3 is a side view of this airplane.

The dominant features of my design reside in portions shown in full lines.

I claim:

The ornamental design for an airplane, or similar article, substantially as shown and described.
